SHOE FORM

William J. De Witt and Isaac Goodfellow, Auburn, N. Y., assignors to Shoe Form Co., Inc., Auburn, N. Y., a corporation of New York

Application August 17, 1935, Serial No. 36,677

8 Claims. (Cl. 12—128.4)

This invention relates to an improvement in a shoe form adapted to be inserted into a shoe to plump out the toe thereof, such form comprising a hollow toe portion of celluloid or other 5 formable material and a cross brace connecting the walls of the toe portion for expanding or contracting the same. Shoe forms of this general type are old and well known and the present invention relates to the cross brace feature and 10 more particularly the form and operation thereof.

The primary object of this invention is to provide in a shoe form a cross brace, which may or 15 may not consist of two sections, pivoted at one end to one wall of the toe portion and having a slot in the other end which receives a stud carried by the other wall of the toe portion, said slot having a plurality of notches or recesses in one or both walls thereof.

Another object of this invention is to provide in 20 a shoe form a cross brace made up of two pivotally connected sections which act as a toggle whereby the toe portion may be easily inserted into and removed from the toe of a shoe.

These and other objects will appear from a consideration of the following description and of the drawing which form a part thereof and in which,

Fig. 1 is a side elevation of a shoe form embodying this invention inserted in the toe of a shoe;

Fig. 2 is a plan view of a form with the upper removed illustrating one embodiment of this invention, the form being fully expanded;

Fig. 3 is a view similar to Fig. 2, the form being partially contracted;

Fig. 4 is a cross sectional view taken along the line 4—4 on Fig. 2; and

Figs. 5 and 6 are views similar to Fig. 2 illustrating other embodiments of this invention.

The shoe form 10 includes a toe portion 11 40 the walls of which terminate in ball flanges 12 and 13. As shown in Fig. 1 the toe portion 11 is adapted to be inserted in the toe 14 of a shoe to plump out the toe thereof. The practice of using the form is, as is well known, to contract the 45 walls of the shoe form, insert the contracted form into the toe of a shoe and expand the walls of the form the proper distance to give the toe of the shoe the desired appearance. The shoe form is withdrawn from the shoe by reversing the 50 above order of operations. These treatments of the shoe form are carried out by means of the cross brace the structure and operation of which will now be described.

The cross brace 15 of the toe form embodiment illustrated in Figs. 2, 3, and 4 comprises sec-

tions 16 and 17 pivotally joined at their overlapping inner ends by a stud or rivet 18. The outer ends of the sections are pivotally secured to the toe form flanges, the section 16 being attached to the flange 13 by a stud or rivet 20 which is carried by the flange and passes through an arcuate slot 21 in the section. Thus the section 16 has only a pivotal movement relative to the flange 12 while the section 17 has both a pivotal and a longitudinal movement relative to 10 the flange 12.

In one or both walls of the slot 21 are formed recesses 22 which receive the shank of the stud or rivet and removably hold the section 17 in any one of several positions whereby as pointed out above the expansion of the toe form can be adjusted. A tongue 23 projects upwardly from the inner end of the section 16. The tongue is preferably but not necessarily integral with the section 16 and is located at the outer edge thereof. The tongue thus serves to facilitate the pivotal movement of the section 16 about the rivet 19 for moving the sections 16 and 17 into or out of alignment and further serves to limit such movement in one direction.

The form when inserted in a shoe is first, contracted by swinging the cross brace sections out of alignment (Fig. 3), second, inserted into the shoe toe and third, expanded by bringing the cross brace sections into alignment (Fig. 2). When the stud 20 is at the bottom of the slot 21 as shown in Fig. 2 the walls of the form are fully expanded. Under many conditions however such full expansion is not desired and the usual procedure is, before the form is inserted into the shoe, to shift the section 17 so that the stud 20 is at the top of the slot and, after the sections have been brought into alignment, to apply further pressure on the tongue 23 so that the cross brace swings as a unit about the stud 19 until the toe of the shoe has been plumped out sufficiently.

The cross brace 25 of the embodiment shown in Fig. 5 is made of a single strip pivoted at one end upon a stud 26 carried by the flange 12 and having at the other end a notched slot 27 which receives a stud 28 on the flange 13. The tongue 29 is struck up from the body of the cross brace. The movement of the cross brace preferably by grasping the tongue 29 causes the cross brace to swing about the stud 26 the slot 27 being moved relative to the stud 28 to expand or contract the walls of the form.

The cross brace 30 of the form shown in Fig. 6 like that shown in Fig. 5 is movable only as a

55

unit. It however consists of two sections joined together, to wit, a rod 31 and a plate 32 suitably connected. As shown in the drawing the rod 31 is pivoted at one end to a stud 33 on the flange 5 12 and is secured at the other end to a stud 34 on the plate 32 being held against movement relative to the plate by suitable clips 35. A notched slot 36 in the plate 32 receives a stud 37 on the flange 13. A pivotal movement of the 10 cross brace about the stud 33 obviously causes the cross brace to expand or contract the walls of the form by the interaction of the slot 36 and stud 37.

While certain embodiments have been shown 15 and described it will be understood that we are not limited thereto and that other embodiments may be made without departing from the spirit and scope of our invention as set forth in the following claims.

20 We claim:

1. A shoe form comprising a unitary hollow toe portion and a cross brace connecting the walls thereof, said cross brace being pivoted at one end to one wall of the toe portion and having at the 25 other end an arcuate slot which receives an element carried by the other wall of the toe portion, both walls of said slot having recesses adapted to receive said element and removably position the cross brace whereby the pivotal movement of the 30 cross brace causes the slotted end to move relative to the element and thereby expand or contract the walls of the toe portion.

2. A shoe form comprising a unitary hollow toe portion and a cross brace, said toe portion having ball flanges extending inwardly from the 35 bottom of both side walls and studs carried by said flanges one on each and said cross brace being pivoted at one end upon the stud carried by one flange and having at the other end an arcuate slot which receives the stud on the other flange, both walls of said slot having recesses 40 adapted to receive said stud and removably position the cross brace whereby the pivotal movement of the cross brace causes the slotted end to move relative to the stud and thereby expand or contract the walls of the toe portion.

3. A shoe form comprising a hollow toe portion and a cross brace, said toe portion having flanges at both side walls and studs carried by said 50 flanges one on each and said cross brace being pivoted at one end upon the stud carried by one flange and having at the other end an arcuate slot which receives the stud on the other flange, a side wall of said slot having spaced recesses into 55 which the stud enters and is removably held, whereby the pivotal movement of the cross brace causes the slotted end to move relative to the stud until the latter enters a recess when the walls of the toe portion are separated the desired distance, and means on the cross brace intermediate the ends thereof for facilitating the movement of the cross brace.

4. A shoe form comprising a unitary hollow toe portion and a cross brace, said toe portion 60 having ball flanges extending inwardly from the bottoms of both side walls and studs carried by said flanges one on each, and said cross brace consisting of two sections, one end of one section

being pivotally joined to one end of the other section, the other end of the first named section being pivoted to one flange by the stud thereon, and the other end of the second named section having an arcuate slot therein which receives the stud on the other flange and means for moving said sections into alignment and said cross brace as a unit about the stud on one flange, the engagement of the slot with the stud on the other flange causing the walls of the toe portion 10 to expand.

5. A shoe form comprising a hollow toe portion and a cross brace, said toe portion having flanges at both side walls and studs carried by said flanges one on each, and said cross brace consisting of two sections, one end of one section being pivotally joined to one end of the other section, the other end of the first named section being pivoted to one flange by the stud thereon, and the other end of the second named section having 20 an arcuate slot therein which receives the stud on the other flange, one side wall of the slot having a plurality of spaced recesses into which the stud enters and is removably held and means for moving said sections into alignment and said 25 cross brace as a unit about the stud on one flange, until the stud on the other flange enters a recess in said slot and the side walls of the toe portion have been sufficiently expanded.

6. A shoe form comprising a hollow toe portion and a cross brace, said toe portion having flanges at both side walls and studs carried by said flanges one on each, and said cross brace consisting of two sections, one end of one section being pivotally joined to one end of the other 35 section, the other end of the first named section being pivoted to one flange by the stud thereon, and the other end of the second named section having an arcuate slot therein which receives the stud on the other flange, and a tongue projecting upwardly from one section for moving the 40 sections into alignment at which time the tongue engages the other section to limit independent movement of the sections, and for moving the cross brace as a unit to separate the side walls of 45 the toe portion.

7. A shoe form comprising a unitary hollow toe portion and a cross brace, said toe portion having ball flanges extending inwardly from the bottoms of both side walls and studs carried by 50 said flanges one on each, and said cross brace consisting of two sections joined together, one end of one section being pivotally attached to the stud on one side flange and the other section having an arcuate slot therein which receives the 55 stud on the other side flange.

8. A shoe form comprising a hollow toe portion and a cross brace, said toe portion having flanges at both side walls and studs carried by said flanges one on each, and said cross brace consisting of two sections joined together, one section being a rod pivotally attached to the stud on one side flange and the other section being a plate having an arcuate slot therein which receives the 60 stud on the other side flange.
